CHARLES H. MUCKENHIRN, OF DETROIT, MICHIGAN, ASSIGNOR TO THE STANDARD SANITARY MANUFACTURING COMPANY, OF PITTSBURGH, PENNSYLVANIA, A CORPORATION OF PENNSYLVANIA.

METHOD OF FLUSHING CLOSET-BOWLS.

1,251,268.

Specification of Letters Patent. Patented Dec. 25, 1917.

Application filed June 9, 1914. Serial No. 843,967.

To all whom it may concern:

Be it known that I, CHARLES H. MUCKENHIRN, a citizen of the United States, residing at Detroit, in the county of Wayne and State of Michigan, have invented certain new and useful Improvements in Methods of Flushing Closet-Bowls, of which the following is a specification, reference being had therein to the accompanying drawing.

10 This invention relates to an improved method of flushing closet bowls, and has for its object the provision of a method which will accomplish better results than is possible of attainment by the employment of an ordinary "siphon action," and to eliminate the many objections incident to the so-called "siphon jet" bowl which is the one most commonly in use at the present time.

The invention embraces the method of discharging the contents of closet bowls consisting of subjecting said contents to the expelling force of water delivered in such a manner as to embody the application of the dynamic properties of a cycloid, comprehend in that particular both the setting up of a siphon action in the bowl and the starting and sustaining of such a siphon action.

In connection with a bowl of the "siphon action" type, the same originally contemplated and still involves the use of a volume of water, customarily delivered through a flushing rim, to augment the body of water usually contained in the bowl so as to raise the level of such body of water (to varying degrees within the limits of several inches) and to cause the water to flow over the dam at the upper end of the up-leg or discharge from the bowl and into and through the down-leg thereof, such escaping water overcoming the air pressure in the down-leg and causing a rush of water therethrough which effects the siphoning of the water in the bowl and the other bowl contents out through the up-leg to free the bowl thereof. The operation stated has objections in that provision must be made in the bowl to permit the rise of the water, as stated, and because of the fact that when the siphon breaks any of the bowl contents remaining in the up-leg flows back into the bowl.

In keeping with what is styled the "siphon jet" action, effort has been made to supple-

ment the volume of water by force, through the medium of a jet introduced into the up-leg of the bowl, usually near the bottom thereof, and which jet discharges up the up-leg and over the dam to effect the siphoning action aforesaid. This is the more advanced type of bowl at present known to the trade, 55 but in the use thereof it will be appreciated that the jet has no cleansing action on the bowl and the necessity for the jet orifices or nozzle requires a very delicate and special handling of the bowl in the construction 60 thereof, such bowl being made by hand. The necessity for forming these bowls by hand renders them very expensive and always attended by the liability that the jet passage will contain defects or be wrongly 65 constructed, which cannot be ascertained until the bowl is completed and placed in use.

It is with a view of overcoming the objections of the prior methods of flushing a bowl, and apparatus for carrying the same 75 into effect, that the present method has been devised, the same consisting in providing the closet bowl with the usual seal-water, and delivering to and causing to pass through such bowl and out of the up-leg 80 thereof water caused to pass through the bowl in a curved path constituting the arc of a cycloid, the last mentioned water being a portion of the usual flushing water, as distinguished from the previously mentioned siphon jet apparatus wherein the water for the jet is diverted away from the flushing supply. The method of closet operation acquired by the introduction of the cycloid differs from the siphon methods in 85 that the water flowing along the cycloid reaches the lowest point of the curve i. e. at the bottom of the up-take leg more quickly than the water following the walls of the bowl cavity elsewhere, the result being that the flow of water is started up the up-leg much sooner than would be the case in a true siphonic action. The function of the jet in the previous method referred to being to start the flow up the up-leg independent of the flow into the bowl cavity, the action described as acquired through the cycloid is therefore substantially that of the jet but with no diverging of the flushing water from the bowl cavity. A property of 90 the cycloid being to change the direction 95

from the vertical to the horizontal without loss of energy, as distinguished from the retardation or loss of force incident to the use of a curved surface not a cycloid, said energy 5 may be utilized to expel the bowl contents through the up-leg, thus dispensing with the special construction usually required to afford a jet with its attending difficulties in manufacture under the prevailing hand 10 pressing or molding process.

I have above discussed that phase of my method embracing the starting up of a siphon action in the bowl contents through the medium of water delivered into the 15 bowl in a manner to embody the dynamic properties of a cycloid, and would now re-iterate that the invention also embraces the further step of sustaining such siphon action by causing water to pass down the usual 20 down leg of the bowl in a curved path similarly constituting the arc of a cycloid to effect a temporary water plug across the ultimate outlet from the bowl as will hereinafter more fully appear. In carrying the 25 method into practical effect I prefer the assistance of an apparatus designed to that end, and to impart a better understanding of the invention, reference will be made to the accompanying drawings forming part hereof 30 and wherein the preferred construction is illustrated.

In the drawings:

Figure 1 is a vertical longitudinal section through the bowl,

Fig. 2 is a horizontal sectional view thereof on line 2—2 of Fig. 1.

Referring more specifically to the drawings wherein like reference characters designate corresponding parts in the several views, it will be observed that the bowl cavity is substantially oval in its upper part 40 and from the flushing rim 1 to about the level at which the seal water stands, that is, from the rim to about the level of a plane 45 on line 2—2 drawn across the top of the dam 2^a, the walls of the bowl extend directly downward with very little contracting curvature. From the line 2, the lower portion 50 of the bowl contracts more sharply and the front and rear quarters or thereabout are constructed with curvatures that constitute a true cycloid in the bowl cavity, the rear portion being the bottom of the up-leg 4.

I prefer to construct this part of the bowl 55 so that each arc extending from the focus 3 is substantially the arc of a cycloid having a half longitudinal axis equal to the distance from 5 to 2, and a vertical axis equal to the distance from 5 to 3, the distance from 60 5 to 2 being the half of the developed perimeter of a circle whose diameter is equal to the vertical distance from 3 to 5.

It is a well known characteristic of this cycloidal curve that an article dropping 65 along its curved surface will have greater

velocity than when moving over surfaces of other curvatures of a distinctly different nature, and the same velocity as if dropped directly along the vertical axis and that its acquired velocity or momentum will carry 70 it up the opposite curve of the cycloid to a height equal to that from which it drops. Of course, curves that are not cycloids but approach to a cycloid will produce results which approach to the results produced by 75 the cycloid and therefore the action which is to be carried out by the cycloidal curves can be attained by any other curve which approaches to the cycloid and would come within the spirit of the invention which is 80 involved in the use of this curve selected as best for the purpose.

The cycloidal surface of the bowl between the points 7 and 8 (constituting about the front quarter of the bowl) is produced as a 85 curved surface of revolution by swinging its curve on a line somewhat in front of its vertical axis. A surface accomplishing good results can be constructed by arranging cycloidal curves generated by circles of different sizes in a way such that the high points are in the desired arc around the bowl and the low point (where the curve is nearly horizontal) crosses at the mouth of the discharge leg, the crossing point should 90 be near (but is not necessarily directly at) the center of the discharge intake, the requisite being that the momentum of the water falling along the surface shall tend to carry the mass into the discharge passage, 100 the object being to produce a concentration of whatever water comes through the flush rim and strikes the front quarter of the bowl, concentrating all of the dropping water to a focus which is near the middle of the 105 mouth opening into the discharge leg 4. The flushing rim is provided with openings along the bowl surface through which the water drops from the rim into the bowl in the ordinary way, with a provision however, that a large part of the water drops through the front quarter and drops into contact with the curved interior of the bowl and is concentrated as it drops to the focal point at the mouth opening of the discharge 110 leg. This water drops with the force that it acquires by dropping from the flushing rim added to such force as may remain to it from its previous travel due to the height of the flush tank above the bowl.

From the focal point 3 the water passes as a mass or stream up the curved lower run of the leg 4; this has a force sufficient to carry all the water that drops into the bowl over the dam, provided it is not impeded by 125 seal water in its course from the rim of the dam. If there be seal water, as is always the case at the first part of the action, the momentum of the dropping water is sufficient to start the seal water in motion, and 130

very soon sets up the siphonic action which will be referred to hereafter and continues to keep the seal water in motion until the seal water has been entirely discharged and 5 is followed by the stream of flush water dropping through the rim concentrating at the focal point and passing as a stream up the discharge leg and over the dam.

The down leg of the discharge passage is 10 constructed with a chamber between the dam 2^a and the final outlet opening 10 which is sufficient to hold any excess water over that which passes through the up-leg during the period of flush beyond that which in the 15 first part of the flush passes out through the outlet opening 10.

The rear of the discharge leg is curved along its under run with a half cycloid or a curve approaching a cycloid in character, 20 which causes the water that drops over the dam to leap across the opening of the final discharge outlet 10 from the point 12 to the surface above the point 13 (shown in the drawing as located slightly below the point 25 12) to allow for a slight drop of water by gravity at this point, but which lower location of the point 13 is not an essential feature to the action, as some part of the water leaping from the under run of the discharge conduit will strike above the point 13 and even 30 above the level of the point 13, inasmuch as the water is in a mass and much of it is raised above the surface of the under run of the curve.

35 Some of the water leaps across the opening 10, strikes the curved surface 15 and curves upward and backward, much of it adhering to the surface and following a curved path and some of it spattering or 40 flying, but nearly all of it remaining in the portion of the chamber which is above the direct outlet for an instant of time, and the water thus accumulates at this point before it changes its direction of movement 45 downward through the ultimate outlet 10. This change of movement and delay in time is sufficient to very promptly produce a water plug at this point and as soon as the water plug is established the water tends 50 to accumulate more and more and fill up the chamber E which now serves to store the excess water passing over the dam, exceeding for a short time the water escaping through the outlet F.

55 I have utilized in this bowl the feature of employing the momentum of the falling water in the body of the bowl itself, and which is all used for the purpose of washing the surface of the bowl, for the purpose of continuing to carry out the flush water after 60 the contents or original seal water has been discharged and thus substantially preventing the action attendant upon the breaking of the siphon, and experiment has shown

that these results are very successfully attained in the construction that is herein shown.

The seal water is carried out much more promptly and almost without the ordinary rise of the seal water in the bowl and before 70 siphonic action begins, for example, in standard bowls of various kinds that I have tested the rise of the seal water is from one and one-half to three inches before the siphon action was established, whereas, in a 75 bowl constructed according to this invention, the rise of the seal water is barely half an inch, while the siphon action is established within three seconds, and the seal water is discharged within five seconds, the 80 after flow continuing during the period of the flush which usually lasts from eleven to twelve seconds, and there is no visible return following the breakage of the siphon, 85 a feature which invariably happens with the ordinary siphon discharge bowl which is not aided with a jet.

I am not aware of any term or phrase that will exactly and briefly characterize the geometrical figure which I have described. 90 Therefore considering it analogous to an elliptic spheroid I will call this figure a cycloidal spheroid and will call the part between two consecutive diverging planes that are bounded by unequal cycloids a sector 95 of a differential cycloidal spheroid.

Having thus described the invention, what is claimed is:—

1. The art of emptying the contents of 100 closet bowls by the employment of the dynamic properties of a cycloid consisting in causing an expelling volume of water to follow the arc of a cycloid downward and toward the bowl discharge and causing flushing water to enter the bowl cavity during 105 the operation.

2. The art of emptying the contents of 110 closet bowls by employing the dynamic properties of a cycloid consisting in causing flush water to enter the bowl, converting the flush water entering the bowl opposite the discharge thereof into an expelling jet by causing it to flow downwardly and toward the discharge in the arc of a cycloid.

3. The art of emptying closet bowls 115 consisting in projecting into the bowl a volume of flushing water and causing a portion of the flushing water remote from the bowl discharge to follow the arc of a cycloid and converge at a point centrally of the discharge to effect a preliminary jetting action through the discharge.

4. The method of emptying the contents 120 of vessels comprising the subjecting of said contents to the discharging action of a liquid moving toward the exit from said vessel in the path of a cycloidal curve to derive the dynamic properties thereof.

5. An apparatus of the character described, comprising a vessel having a suitable exit portion for the vessel contents, a surface within the apparatus shaped to form 5 a cycloidal curve, and means for discharging a liquid into the apparatus to cause the same to move over the cycloidal surface toward the said exit to derive the dynamic

properties of the cycloid in discharging the contents of the vessel. 10

In testimony whereof I hereunto affix my signature in the presence of two witnesses.
